LADY'S SHOE

Beth Levine, New York, N.Y.

Application March 20, 1959, Serial No. 55,089

Term of patent 14 years

(Cl. D7—7)

The characteristic features of the design reside in the portions shown in full lines.

I claim:

The ornamental design for a lady's shoe, substantially as shown and described.
